John H. Jenner

UNITED STATES PATENT OFFICE.

JOHN HENRY JENNER, OF LEAVENWORTH, INDIANA.

WAGON-BRAKE.

SPECIFICATION forming part of Letters Patent No. 691,547, dated January 21, 1902.

Application filed July 22, 1901. Serial No. 69,289. (No model.)

To all whom it may concern:

Be it known that I, JOHN HENRY JENNER, a citizen of the United States, residing at Leavenworth, in the county of Crawford and State of Indiana, have invented certain new and useful improvements in Wagon-Brakes; and I do declare the following to be a full, clear, and exact description of the invention, such as will enable others skilled in the art to which it applies to make and use the same.

The object of my invention is to provide a wagon-brake which is simple of construction, easily and conveniently operated, and adapted to be quickly applied and removed.

To this end the invention consists of certain novel features of construction, combination, and arrangement of parts, as will be hereinafter more fully described, and particularly pointed out in the appended claim.

In the accompanying drawings, Figure 1 is a perspective view of the rear portion of the running-gear of a wagon, showing the application of the invention thereto. Fig. 2 is a top plan view thereof. Fig. 3 is a cross-section on line 3 3 of Fig. 2, and Fig. 4 is a similar view on line 4 4 of Fig. 2.

Referring now more particularly to the drawings, the numeral 1 designates the rear axle, the numeral 2 the rear wheel, and the numeral 3 the rear hounds of a wagon or vehicle of ordinary or any preferred construction.

Pivottally mounted upon the forward portion of the handle 3 is a transverse bar 4, which is provided with loops or bearings 5, in which is mounted a swinging yoke or hanger 6. This hanger is of U form and has its arms projecting downwardly, and to said arms is connected by upper and lower sets of nuts 7 and 8 the brake-beam 9, carrying the brake-shoes 10, which are adapted to bear against the wheels 2. By this construction the brake-beam is mounted to swing upon the bar 4 toward and from the wheels 2 and may be applied to and released from the hanger 6 by applying or releasing the nuts 7 and 8 in a manner readily understood. The brake mechanism, with the exception of a single brake-rod, is mounted upon said beam, so that it can be applied to and removed from the frame with the beam.

Journalized in bearings 11 upon the rear portion of the beam 9 is a shaft 12, provided with cranks 13 and 14. The crank 13 is joined to the forward end of a brake-rod 15, which is connected at its rear end to the rear axle 4. The crank 14 carries loops or sockets for the reception of a hand-lever 10, which is suitably secured thereto, so that by operating the lever back and forth the brake-shoes will be operated and released in the manner herein-after described.

Pivoted to the crank-arm 14 is a ratchet-toothed L-shaped bar 16, the teeth of which are adapted to engage or slide upon a fixed pawl or projection 17 on the front edge of the beam 9. This ratchet-toothed bar has connected thereto a rod 18, which is operated by a pivoted hand-lever 19 to engage and release the bar whenever desired.

In operation, when the lever 10 is thrown forwardly the crank-shaft 12 is turned to bring the crank 13 to an upright position, whereupon the brake-beam 9 is drawn rearwardly and the brake-shoes 10 brought into contact with the wheels 2. When, on the other hand, the lever is thrown rearwardly, the crank 13 is moved to a horizontal position, lengthening, instead of decreasing, the distance between the brake-beam 9 and the rear axle 4, thus causing the brake-beam to swing forwardly on the movable hanger 6 and to thereby withdraw the brake-shoes from engagement with the wheel. When the crank-shaft is adjusted to the desired position to hold the brake in and out of action, the ratchet-toothed bar is engaged with the fixed pawl to hold said shaft against movement, and when this is done the brake-beam is prevented from swinging and the brake-shoes are held in engagement with the wheels. When the lever is thrown in the opposite direction to release the brake-shoes from engagement with the wheel and the ratchet-toothed bar is engaged with the fixed pawl, the shaft is also held against movement and the brake-beam thereby held retracted and prevented from swinging on the transverse bar 5. Any other suitable form of latch mechanism may be employed in place of the fixed pawl and ratchet-toothed bar to perform this function.

When the brake mechanism is used upon

box vehicles, the operating handle or lever herein shown may be dispensed with, and suitable connections provided by which the crank-shaft may be operated from the front 5 of the vehicle.

From the foregoing description, taken in connection with the accompanying drawings, the construction, mode of operation, and advantages of the invention will be readily understood, and it will be seen that the invention 10 provides brake mechanism of which the operating parts are carried solely by the brake-beam and are readily and conveniently removable therewith.

Changes in the form, proportion, and minor 15 details of construction may be made within the scope of the invention without departing from the spirit or sacrificing any of the advantages thereof.

Having thus described my invention, what

I claim, and desire to secure by Letters Patent, is—

In a vehicle-brake, the combination with a rear axle, wheels and hounds of a vehicle, of a brake-beam mounted to swing upon said 25 hounds, a rock-shaft mounted upon the beam and provided with cranks at its ends, a connection between one of the cranks and the rear axle, operating mechanism connected with the other crank, and a latch for connecting the rock-shaft with the beam to hold 30 said shaft against independent rotatable movement, substantially as described.

In testimony whereof I have hereunto set my hand in the presence of two subscribing 35 witnesses.

JOHN HENRY JENNER.
